ABSTRACT OF THE DISCLOSURE

A remote identification system comprises a plurality of electronic relay circuits each capable upon actuation of causing the flow of a similar increment of current. The relay circuits are coupled each to the next in a series such that actuation of any one of the relay circuits causes the actuation of the next following relay circuit of the series. There are also a plurality of detectors each associated with and coupled electrically to a respective one of the relay circuits for actuation thereof when the associated detector operates, a common conductor connected to all of the relay circuits. There is a current-amplitude responsive device connected to the common conductor for indicating the sum total of the increments of current caused to flow in the common conductor as a result of actuation of any one relay circuit by its associated detector with resultant actuation of the other following relay circuits of the series.

This application is a continuation-in-part of my co-pending application, Ser. No. 406,388, filed Oct. 26, 1964.

The present invention relates to means for identification from a distance, and has as its object the provision of a method and an apparatus by means of which it is possible to monitor the operation of, and to identify, a supervisory detector belonging to a network of automatic monitoring and alarm devices adapted to respond to external stimulations produced by any appropriate physical, chemical or physico-chemical agent.

By way of non-limiting example, there may be mentioned the application of the apparatus to fire detection or to the combination of a network of fire detectors with proximity (anti-theft) detectors, means for detecting the opening and closing of doors and, in general, any apparatus whose essential function is to provide an alarm, to trigger counter-measure systems or automatic prevention devices.

In British patent specification No. 1,081,974 the applicants have described a method and an apparatus which achieve this result. This method consists essentially in providing a pulse generator in association with each detector of the network, in placing the output circuits of these generators in series by connecting them to a device situated at a central station, so that when one of the generators emits a pulse as a result of the operation of the detector with which it is associated, this pulse brings about the operation of the succeeding generator, whereby there arrives at the central station a train of pulses, the number of which is equal to the number of generators situated between the central station and the generator which was the first to operate, so that the latter may be identified by reading a counter which totals the pulses received.

The system referred to operates completely satisfactorily, but it has one disadvantage and one deficiency.

The disadvantage of the said system resides in that, when the network is returned into service, it may happen

2

that one of the pulse generators employed does not return to its initial state and is therefore incapable of acting in a subsequent sequence, which may result in difficulties in the subsequent counting operations.

The deficiency of the known system consists in that it is not duplicated by a monitoring means.

The present invention obviates the said disadvantage and rectifies the aforesaid deficiency.

These objects are achieved by providing a constant-current generator in association with each of the detectors of a network, by connecting the outputs of the generators in such manner as to collect, in a line terminated at the central station by an appropriate indicating device, the sum of the currents emitted by the sequentially actuated generators, whereby it is possible to identify the generator from which the summation started, i.e. to identify the generator and thus the detector which were the first to operate.

It will be seen that a system comprising the two variants of the method of location by pulse counting and by summation of the currents avoids the aforesaid objections to the said earlier system referred to, because the indicating system of this invention will continue to give an indication, when the installation is returned into service, in the event of one of the generators not having returned to its initial state in which it transmits no current.

On the other hand, it is possible by reading the indicating device of the new system to verify whether the count read at the pulse generator is correct. Any discrepancy between the readings of the indicating device and of the counter will reveal state of disturbance.

By using only the second variant involving the summation of the currents, it is possible to provide a simple installation which may be sufficient in many cases, although it does not exert any duplicate monitoring as indicated above.

FIGURE 1 of the accompanying drawing is a circuit diagram having a network of detectors arranged according to the invention. A series of signal generators 2A, 2B, . . . 2N are provided each in association with a respective one of a series of detectors 1A, 1B, . . . 1N. The signal generators are so arranged that the operation of one of them actuates the succeeding generator, and so on, in cascade, up to the last one. Each actuated generator transmits a signal along the line 4.

In accordance with the present improvement, the generators 2A, 2B, . . . 2N supply constant current. These generators may be of any type known per se, for example of the type comprising thyratrons, semiconductors, etc.

Each time one of these generators is actuated, it feeds and continues to feed a constant-current signal along the line 4, so that the strength of the current flowing through the line 4 is equal to the sum of the currents emitted by all of the generators which happen to have been sequentially actuated. If I is the current of a generator and m the number of sequentially actuated generators, the current strength along the line 4 will be mI . This strength, which is measured on a measuring instrument 5, e.g. an ammeter, therefore determines the number of generators which have been actuated in the network, and thus identifies the detector which has produced the alarm. Thus, if the detector 1A operates, for example as a result of the appearance of smoke revealing the commencement of a fire, it actuates the generator 2A associated therewith. This generator transmits a constant-current signal I along the line 4 and energizes the succeeding generator 2B through the link 3. The generator 2B in turn transmits a signal I along the line 4 and energizes the succeeding generator 2C, and so on until the last generator 2N has operated and emitted a

signal I. There will thus have been set up along the line 4 a signal current of amplitude NI which is measured at the indicating device 5. The latter may be a milliammeter or an ammeter, optionally graduated in numbers of detectors, or again an electronic voltmeter or even both when the number of detectors installed is large; the milliammeter may then give a coarse indication (tens, hundreds, for example) and the electronic voltmeter a precise indication in this range.

In the system thus constructed, it will be seen that when the network of detectors is returned into service from the central station by a device such as that described in the aforementioned patent, if a detector does not return to its initial state the generator associated therewith will continue to supply a signal I along the line 4, so that a reading will continue to be present at the device 5 and the operator may immediately detect the defect. If, for example, the detector 1B does not return to its initial state, the generator 2B emits its signal I and energises the generator 2C, as described in the foregoing, and so on. In this case, the device 5 identifies the detector 1B by the number N-1, since (N-1) generators have remained in circuit.

This system therefore affords complete security. On the other hand, if it is combined with a counting device, as diagrammatically illustrated at 7, it will be appreciated that the device 5 makes it possible to check the readings of the counter, whereby the reliability of the system is doubled.

Referring now to FIGURE 2 D₁, D₂, D₃ . . . D_n are a series of detectors arranged in such a manner that when one of these detectors becomes operative, an electrical current issued from a battery B flows through their corresponding resistors R₁, R₂, R₃ . . . R_n. All detectors D are connected in such a manner that when one of them becomes operative, it renders the device next to it in the series operative, and so on along the series.

This means that through meter M there will flow a current which is equal to the current of one detector multiplied by the number of operative detectors and the reading of meter M will therefore permit the identification of the device which was first to operate.

For example, if there are twenty detectors, such as D₁, D₂, . . . D_n, then when one of them is operative, a current of ten millamps flows across each resistor R₁, R₂, . . . R_n.

It is obvious that if the detector which is twelfth in the series measured from the meter end is rendered operative, the eleven detectors following it will also be rendered operative, so that meter M will deflect to 120 millamps, and that reading is specific to the twelfth detector, which is accordingly indicated to the user.

The detectors may include, for example, relays in a sequential distribution, or valves, silicon controlled rectifiers, thyratrons, (hot or cold) and transistors. In fact any controllable device capable of delivering a predetermined amount of electrical current can be used.

FIGURE 3 shows a preferred way of carrying out the invention with the use of silicon controlled rectifiers or solid state thyratrons.

In this case D₁, D₂, D₃ . . . D_n, are detectors in the form of sensing elements designed in such a manner that they can provide enough power to actuate the corresponding silicon controlled rectifiers, Q₁, Q₂, Q₃, . . . Q_n, which are cathode loaded by resistors R₁, R₂, R₃, . . . R_n.

It is presumed that all the silicon controlled rectifiers are identical and that all the loading resistors are identical.

If one of the detector-sensing elements actuates its rectifier, the next sensing element is excited and also actuates its rectifier, and so on to the last rectifier of the chain, in the direction towards the meter M.

Therefore each of the operative silicon controlled rectifiers will provide meter M with a current which is identical for each unit and therefore the current across M will be the sum of the currents of all those devices which have become operative.

Accordingly, the reading of M will permit immediate location of the initially operated detector.

In practice, detectors D₁, D₂, D₃, . . . D_n, may be any suitable type of detecting element and Q₁, Q₂, Q₃, . . . Q_n may be any suitable type of silicon controlled rectifier or thyristor or any electrical or electronic bistable device (on-off) while R is essentially defined by the value of the full scale deflection of the pointer of M divided by the number of detecting units.

It will be obvious that the solution afforded by the invention of the present application, when employed alone, is reliable since it is not attended by the previously mentioned disadvantage, and economical, since it only involves the use of a simple and inexpensive measuring device. This solution is ideal in cases where double safety is not required.

I claim:

1. A remote identification system comprising a plurality of electronic circuit means each capable upon actuation of causing the flow of a similar increment of current, said plurality of means being coupled each to the next in a series such that actuation of any of one of said circuit means causes the actuation of the next following circuit means of the series, a plurality of condition sensing means each associated with and coupled electrically to a respective one of said circuit means for actuation thereof when the associated condition sensing means operates, a common conductor connected to all of the circuit means, and a current-amplitude responsive means connected to said common conductor for indicating the sum total of the increments of current caused to flow in the common conductor as a result of actuation of any of one circuit means by its associated condition sensing means with resultant actuation of all of the other following circuit means of the series.

2. A remote identification system, as claimed in claim 1, wherein each circuit means has a respective impedance in series therewith, the plurality of circuit means being all coupled in parallel across a current source.

3. A remote identification system, as claimed in claim 2, wherein the circuit means are thyratrons.

4. A remote identification system, as claimed in claim 2, wherein the circuit means are semiconductor devices.

5. A remote identification system, as claimed in claim 1, wherein the current-value indicating device is an ammeter.

6. In combination, a remote identification system as claimed in claim 1, and a counter means connected to said common conductor and arranged to count the number of incremental changes of current value resulting from actuation of any one circuit means by its associated condition sensing means with resultant actuation of the other following circuit means of the series.
